UNITED STATES PATENT OFFICE.

OSCAR A. SMITH, OF CLEVELAND, OHIO, ASSIGNOR OF ONE-HALF TO WILLIAM R. MITCHELL, OF CLEVELAND, OHIO.

BINDING POST.

1,420,770.

Specification of Letters Patent. Patented June 27, 1922.

Application filed August 2, 1919. Serial No. 314,884.

To all whom it may concern:

Be it known that I, OSCAR A. SMITH, a citizen of the United States, residing at Cleveland, in the county of Cuyahoga and 5 State of Ohio, have invented certain new and useful Improvements in Binding Posts, of which the following is a specification.

This invention relates to binding posts, by means of which an electrical conductor or 10 wire may be attached to one of the elements of a battery cell.

The object of the invention is the provision of an improved binding post, which can be readily and quickly attached to the carbon of a battery by forcing the same into a hole drilled in the carbon without the breaking or splitting of the carbon, and which when in place will be efficiently and rigidly held against improper separation.

20 In the drawings, accompanying and forming a part of this specification, Fig. 1 illustrates the stock cut to the proper length; Fig. 2 illustrates one end thereof threaded; Fig. 3 shows the post with a washer slipped 25 over the smooth portion of the post and up against the threads which act as a shoulder; Figs. 4, 5 and 7 illustrate the several steps in the making of the post shown in Figs. 6 and 8 which latter figure illustrates the complete post with the projections in position to 30 hold the binding post in the carbon against rotation. In Fig. 6 the post is shown inserted into one end of the carbon rod and Fig. 9 is a detail view of the washer which may 35 be used.

Similar characters of reference indicate corresponding parts in the several figures of the drawings.

In the binding post shown in the patent 40 to E. C. Henn, No. 813,093, February 20, 1903, the post is provided with a series of longitudinally extending ribs disposed parallel with the axis of the shank and located in juxtaposition around the post, and as I 45 had considerable to do with the making of devices in accordance with this patent, great difficulty was experienced in fitting these binding posts into the carbon without splitting it as they were driven thereinto. Owing 50 to the number of ribs in this Henn binding post considerable pressure was required to force the post into the carbon which frequently split it, and if a hole was drilled sufficiently large to prevent the splitting of the 55 carbon it prevented the binding post from

being rigidly held in place and consequently it would turn with the terminal nut when rotated or tightened.

The present improved binding post can 60 not only be made much less expensively, but a great saving in the amount of brass required in the manufacture of the post, for in the present improvement the stock can be cut off to the required length and size as 65 illustrated in Fig. 1 by a cutting off machine for the rolling of the thread. The rolling of this thread leaves a shoulder back of the thread, against which a punched washer can be located. The post is then placed in a punch press provided with suitable dies by 70 means of which one or more, usually two or three half circular fins or projections, are formed on the cylindrical portions of the post.

The dies shown in Fig. 4 comprise a pair 75 of members 2 and 3, each having a semi-circular recess therein, as 4, forming when the two members are brought together a cylindrical opening corresponding throughout the major part of the length of the plain part 80 of the stock to the diameter of the stock of the binding post. At the zones where the fins or projections are to be formed about 180° of this cylindrical opening corresponds to the diameter of the stock, while about 90° 85 of each member is built out or of smaller radius as partly shown by dotted lines *a* Figs. 4, 5 and 7. The die members are provided, one with a projection 5 and the other with a semi-circular recess 6 at one side 90 thereof, there being a projection and a co-operating recess for each fin to be formed. In the form of the die for the binding post shown in Fig. 6 there are two projections and two mating recesses located side by side 95 but spaced apart. In the form of binding post shown in Fig. 8 the die is provided with three of these projections and likewise three mating recesses, two at one side of the die members and one at the opposite side in 100 alternation whereby two fins would be formed at one side of the stock and one at the other.

In making these improved binding posts, the stock 7 after being first suitably cut to 105 the desired length is then rolled to have its thread 8 placed therein after which a suitable punched washer 9 is placed on the post and then the plain or smooth portion of the post is placed between the die members, 110

- which are then brought together by the brass to form the fins 10 or 10 and 11 according to the desired number of fins that are to be provided.
- 5 As the die members 2 and 3 are brought together each built out portion *a* and projection 5 will force a portion of the metal of the stock (see Figs. 5 and 6) into the recess 6 and thus form a semi-circular fin or projection as 10 or 11.
- Owing to the shape of the recess 6 and projection 5 which of course may be of various shapes the fins 10 and 11 are shown semi-circular in form and it will be observed 15 that they are obtained by utilizing a portion of the metal of the stock which under pressure is caused to gradually flow, as it were, into the recess 6.
- In the form shown in Fig. 6 as hereinbefore stated two of the fins are located on one tangent of the stock, while in the form shown in Fig. 8 two of the fins are located on one tangent while an alternating fin is located on the opposite tangent of the stock.
- 25 Either form has been found successful in practice and found to be sufficient to hold the post in the carbon and to prevent the turning of the binding post when placed in the carbon.
- 30 Furthermore, the formation of the binding post in the manner described prevents the splitting of the carbon when the post is forced into the drilled hole thereof, especially since the fins are so located away from 35 the end of the post which permits the latter to project quite a distance into the carbon before the fins are brought into engagement with such carbon, and especially because the location of the fins relatively far apart does 40 not in forcing the post into the carbon cause pressure on all parts of the carbon at the same time.
- The projections 5 may be formed by suitable steel hardened circular pins rigidly secured in openings of the die whereby the 45 pins are renewable and replaceable.
- The various details may be more or less changed without departing from the spirit or scope of the present improvement.
- 50 I claim as my invention:
1. A binding post having a threaded portion, a plain portion, and one or more semi-circular fins spaced from the ends of said plain portion.
  - 55 2. A binding post having a pair of semi-circular fins spaced apart at one side of said post.
  3. A binding post having a plurality of lengthwise spaced apart fins at one side of 60 said post.
  4. A binding post having a plain portion, a threaded end, a washer therebetween, and a plurality of lengthwise spaced-apart
- aligned fins at one side of the plain portion of said post.
5. A binding post having a plurality of lengthwise spaced apart fins at one side of 65 said post, and a fin at the opposite side thereof.
6. A binding post having a plurality of 70 spaced apart fins at one side of said post, and a fin at the opposite side thereof.
7. A binding post having at opposite sides a plurality of spaced apart fins.
8. A binding post having at opposite sides 75 a plurality of spaced apart fins, semi-circular in form.
9. A binding post having at the side thereof a plurality of aligned spaced apart fins.
10. A binding post having at one or more 80 sides thereof a plurality of spaced apart fins, semi-circular in form.
11. A binding post having a threaded end, a plain portion, a washer therebetween, and a plurality of aligned spaced-apart fins at 85 one side and at the opposite side a similar fin in staggered relation with said first spaced fins.
12. A binding post having a threaded portion, and a smooth portion, said smooth 90 portion having a plurality of staggered fins.
13. A binding post having a threaded portion, and a smooth portion, said smooth portion having a plurality of staggered fins 95 semi-circular in formation.
14. A battery cell element consisting of a rod of non-metallic substance having a bore in its outer end portion, a binding post adapted to be forced thereinto and having a projecting end provided with conductor attaching means and having the end projecting into said rod provided with one or more semi-circular fins spaced from the inner end 100 of said rod.
15. A battery cell element consisting of a 105 rod of non-metallic substance having a bore in its outer end portion, a binding post adapted to be forced thereinto and having a projecting end provided with a conductor attaching means and having the end projecting into said rod provided with a plurality 110 of lengthwise spaced-apart aligned fins at one side of said post.
16. A battery cell element consisting of a rod of non-metallic substance having a bore 115 in its outer end portion, a binding post adapted to be forced thereinto and having a projecting end provided with conductor attaching means and having the end projecting into said rod provided with a plurality of 120 staggered fins.

Signed at Cleveland, county of Cuyahoga and State of Ohio, this 30th day of July, 1919.

OSCAR A. SMITH.
